Primary Examiner — Mark Goodwin(74) *Attorney, Agent, or Firm* — Saidman DesignLaw Group, LLC(57) **CLAIM**

The ornamental design for a coupler and tip for a ground engaging machine implement, as shown and described.

DESCRIPTION

FIG. 1 is an upper, right-side perspective view of a coupler and tip for a ground engaging machine implement showing my new design;

FIG. 2 is a front view thereof;

FIG. 3 is a rear view thereof;

FIG. 4 is a right side view thereof, the left side view being a mirror image thereof;

FIG. 5 is a top view thereof;

FIG. 6 is a bottom view thereof; and,

FIG. 7 is a bottom, right side perspective view thereof.

The relatively light and dark shade lines indicate contour and not surface decoration.

1 Claim, 5 Drawing Sheets(56)
